UNITED STATES PATENT OFFICE.

EUGENE C. BRIGGS, OF NORWOOD, MASSACHUSETTS.

PHONOGRAPH-RECORD FILE.

Application filed March 2, 1921. Serial No. 449,169.

To all whom it may concern:

Be it known that I, EUGENE C. BRIGGS, a citizen of the United States of America, residing at Norwood, in the county of Norfolk and State of Massachusetts, have invented new and useful Improvements in Phonograph-Record Files, of which the following is a specification.

This invention relates to cabinets particularly designed for holding phonograph records, though in a broader aspect of the invention having other and more general fields of usefulness. A principal object is to provide an improved cabinet equipped with means for holding a maximum number of records in a manner so that any desired record may be quickly and easily inspected without withdrawing the same from its pocket and facilitating the selection of the desired record. A further object is to provide an improved mounting for the individual record pockets that is of simple and inexpensive construction, yet strong and reliable. The foregoing and other objects and advantages of the invention will more fully appear from the following detailed description, and the distinctive features of novelty will be pointed out in the appended claims.

Referring to the drawings:

Fig. 1 is a side elevation of a phonograph cabinet embodying the invention, a portion thereof being broken away in vertical section to better show the features of novelty;

Fig. 2 is a front view of the cabinet;

Fig. 3 is a horizontal section on line 3—3 of Fig. 1;

Fig. 4 is a partial section at the same point further illustrating the manner of moving the record pockets to permit inspection of the records;

Fig. 5 is a side elevation of an individual record pocket;

Fig. 6 is a front edge view thereof;

Fig. 7 is an elevation showing the pintle and hinge mounting for the record pockets;

Fig. 8 is a fragmentary section on line 8—8 of Fig. 5 on a relatively enlarged scale; and

Fig. 9 is an elevation on a reduced scale of a paper blank adapted for making the record pocket of the invention.

10 indicates a phonograph cabinet which may be of usual or suitable construction. In the lower portion of this cabinet, a slide 11 is mounted on ways 12 so that it may be pulled out at the front of the cabinet.

This drawer has a rear upright wall 13, the front and sides thereof being left open. To this rear wall at the top and bottom thereof are secured channel bars 14, 15, these being preferably and as shown, of U-shaped cross section opening at the front. The upper and lower sides of these channel bars are perforated at relatively close intervals as indicated at 16, to afford pivot sockets for the extremities of small rods 17 which constitute pintle pins for holding the individual record pockets. These pintle pins have applied thereto, adjacent the top and bottom thereof, metallic leaf members 18, 19, these members being folded around the rods 17 at an intermediate point with the extremities thereof pressed together side by side. The record pocket 20 is produced of a stout paper blank 20^a folded upon itself along the line 21. This blank is of a height somewhat greater than that of the pocket, providing flaps 22, 23 which are folded inward in overlapping relation and in a manner to close and reinforce the top and bottom of the pocket as indicated at 24. The hinge leaves 18, 19 are inserted through slits 25 adjacent the lines 26, 27 upon which the flaps 22, 23 respectively are folded, so that these hinge leaves lie within the folds of the flaps at top and bottom. The folds of the pocket and the hinge leaves are secured and held in assembled relation by means of eyelets 28 headed therethrough, and the edges of the flaps may be pasted down, with a metallic reinforcing clip 29 secured at the lower front edge by means of an eyelet 30. The pocket preferably has its upper outer corner cut away as indicated at 31 to expose an edge of the record for convenient removal, and it may have a central aperture 32 in accordance with the usual construction. At each side of the series of record pockets thus pivotally engaged with the channel bars 14, 15, I preferably provide protective plates 33, either of thin metal or stout cardboard, these being pivoted by suitable pintles to the last apertures 16 at the ends of the channel bars. In use, when it is desired to select a record, the drawer 11 is pulled out, so that the channel bars 14, 15, are substantially flush with the front of the cabinet, and so that the pockets may be parted at any selected point and swung outward toward the respective sides as indicated in Figure 4, affording free access to any given record for inspection and removal thereof. The channel bars 14, 15

secured to the back 13 provide a strong and rigid mounting for the pintle rods 17, and the individual pockets are supported thereon free of one another and adapted for any required manipulation in the most convenient manner. It is to be particularly noted that the individual pockets produced in the described manner are exceptionally strong and durable, though simple and inexpensive to produce, the integral reinforced edges provided by the flaps 22, 23 united to the metallic hinge leaves at the inner ends thereof reinforcing the pocket throughout and insuring a pocket of maximum strength, and of little weight. I am aware that the invention may be embodied in other specific forms without departing from the spirit or essential attributes thereof, and I therefore desire the present embodiment to be considered in all respects as illustrative and not restrictive, reference being had to the appended claims rather than to the foregoing description to indicate the scope of the invention.

Having described my invention, what I

claim as new and desire to secure by Letters Patent is:

1. A phonograph cabinet comprising a slide drawer open at its front equipped with a horizontally extending bar at the top and also at the bottom of the back thereof, said bars perforated at intervals, and a series of pockets adapted to receive and hold phonograph record discs equipped with pintle rods at the inner sides thereof, the extremities of said rods engaged with the perforations of said bars. 30 35

2. A record pocket comprising a sheet folded upon itself with its edges at top and bottom folded down and up respectively in overlapping relation to reinforce the same, and a pintle rod bearing hinge leaves secured to said reinforced edges. 40

In testimony whereof I affix my signature in presence of two witnesses.

EUGENE C. BRIGGS.
